US00D755873S

(12) **United States Design Patent**
Odashima et al.

(10) **Patent No.:** **US D755,873 S**
(45) **Date of Patent:** **** May 10, 2016**

(54) **DIGITAL CAMERA**

(71) Applicant: **Nikon Corporation**, Tokyo (JP)

(72) Inventors: **Toshiko Odashima**, Yokohama (JP);
Kenichi Soejima, Yokohama (JP)

(73) Assignee: **Nikon Corporation**, Tokyo (JP)

(**) Term: **14 Years**

(21) Appl. No.: **29/518,711**

(22) Filed: **Feb. 26, 2015**

(30) **Foreign Application Priority Data**

Aug. 29, 2014 (JP) 2014-019037

(51) **LOC (10) Cl.** **16-01**

(52) **U.S. Cl.**

USPC **D16/202**

(57) **CLAIM**

The ornamental design for a digital camera, as shown and
described.

DESCRIPTION

FIG. 1 is a front, top and right side perspective view of a
digital camera showing our new design;

FIG. 2 is a rear, top and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view thereof showing the stand in
an open position; and,

FIG. 10 is a rear perspective view thereof showing the stand in
an open position.

The features shown in broken lines in the drawings depict
environmental subject matter only and form no part of the
claimed design. The dash-dotted lines denote the boundary of
the claim and form no part of the claimed design.

1 Claim, 10 Drawing Sheets
